UNITED STATES PATENT OFFICE.

FRED A. WOLF, OF READING, PENNSYLVANIA, ASSIGNOR OF ONE-HALF TO JOHN M. WENZEL, OF READING, PENNSYLVANIA.

SUCTION WASHING DEVICE.

1,115,047.

Specification of Letters Patent. Patented Oct. 27, 1914.

Application filed May 23, 1914. Serial No. 840,407.

To all whom it may concern:

Be it known that I, FRED A. WOLF, a citizen of the United States, residing at Reading, in the county of Berks and State of Pennsylvania, have invented certain new and useful Improvements in Suction Washing Devices, of which the following is a specification.

This invention relates to improvements in washing devices of the class commonly known as hand operated suction washers, in which the device is operated by moving it vertically in a vessel containing clothing and a washing element.

15 The object of the invention is to provide a simple device for effectively cleansing clothing, by forcing the cleansing liquid through the clothing while contained in the receptacle, and it is my intention more particularly to provide a device in which the soap foam on the surface of the water will more surely be forced through the clothing instead of allowing it to lie on the surface while the water only is forced through said 25 clothing.

To this end I have devised a plurality of funnel members, so arranged that when a downward movement of the device is made, the soap foam on the water's surface will 30 be drawn up between two of the funnel members and forced down through the inner or smaller funnel member.

The invention is more fully described in the following specification and clearly illustrated in the accompanying drawing, which 35 represents a central, vertical sectional view of my device.

In the drawing the numeral 1 designates a tubular member, formed at its lower extremity with an outwardly flaring end or funnel, 2, and provided with a closure for its upper end in the form of an operating handle, 3. This tube is formed, at a point some distance above its lower end, with a 45 series of perforations 4. To the outer surface of this tube, slightly above the line of perforations 4, I attach, by means of solder or other simple means, a comparatively large funnel member 5, in inverted position, 50 and whose lower edge lies on a plane slightly above that of the smaller central funnel 2.

The numeral 6 designates a second, relatively large funnel member, attached in like manner to the central tubular member 1, at a point below the line of perforations 4, 55 thus providing an open passageway for the liquid, upwardly between the two larger funnels and downwardly through the central tube, when the device is moved in one direction, and in the reverse direction when 60 the device is moved in the opposite direction.

When the device is placed on the surface of the water containing the soap foam, the inner smaller funnel 2 will contact with the 65 water surface before the outer funnel reaches it, and, inasmuch as the lower one of the large funnels 6, being closed at its top, forms an air cushion therein, the soap foam and water will be forced upwardly 70 between the two large funnels as indicated by the arrow *a*, through the perforations 4, and down the tubular member 1, while the continued downward movement of the device will force the said soap foam and water 75 through the clothing. The upward movement of the device, will, of course, reverse the movement of the water, that is, it will pass up through the central tube and down through the space between the two larger 80 funnel members.

It is evident that with my device, the cleansing action is facilitated, inasmuch as the essential portion of the cleansing element, namely the soap, will be drawn up 85 into the funnel and forced through the clothing, thus obtaining the maximum benefit of the cleansing element.

Having thus fully described my invention, what I claim and desire to secure by 90 Letters Patent is:—

In a device of the character described, a tubular member formed with a flaring lower extremity, and having a closure for its upper end and a series of perforations in its 95 vertical wall; an inverted funnel shaped member whose contracted end is attached to said tubular member at a point above the perforations and having its flaring end above the plane of that of the lower end of 100 the flared tube; a second funnel shaped member whose contracted end is attached to

said tube at a point below the perforations, and having its flaring end depending below the flaring end of the central tube, whereby a circulation of liquid may be maintained through said tube and between said funnels when said device is moved vertically.

In testimony whereof I affix my signature in presence of two witnesses.

FRED A. WOLF.
